Primary Examiner — Susan Bennett Hattan*Assistant Examiner* — Vy Koenig(74) *Attorney, Agent, or Firm* — Barlow, Josephs & Holmes, Ltd.(57) **CLAIM**

The ornamental design for a portable seat, as shown and described.

DESCRIPTION

FIG. 1 is a front perspective view of the portable seat showing the new design in a retracted condition;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of the portable seat in an expanded condition of use;

FIG. 9 is a perspective view of the portable seat of FIG. 1 with the bottom foot member in an inverted mode of use; and, FIG. 10 is a front perspective view of the portable seat in a collapsed stored condition.

The broken lines shown in the drawings depict environmental subject matter and form no part of the claimed design.
